SEALED APPARATUS FOR DEGREASING AND DRYING ARTICLES

Richard Cosway, Penketh, England, assignor to
Imperial Chemical Industries Limited, a corpora-
tion of Great Britain

Application September 10, 1942, Serial No. 457,880
In Great Britain October 3, 1941

9 Claims. (Cl. 202—170)

1

This invention relates to improvements in apparatus for degreasing metal and like non-absorbent articles.

It is known to treat metal and like non-absorbent articles with a volatile solvent such as trichloroethylene either in liquid or in vapour form, or both, so as to remove adherent greasy or oily material. The operation is frequently conducted in an open-topped vessel adapted to contain the solvent and having in the lower part means for heating the solvent, and in the upper part means for limiting upwardly the solvent vapour level. The goods so treated are subsequently dried by lifting them into the upper part of the vessel above the vapour level, when adherent solvent evaporates by reason of the heat content of the goods and the heavy vapour falls back into the solvent zone. The ability of the goods to dry in this way is limited by their heat content and in some cases, as for example when they have hollows which retain solvent, this mode of drying may not be satisfactory. In British Patent No. 466,443 an apparatus for treating articles, particularly metallic articles, with a liquid volatile organic solvent such as trichloroethylene is described in which the cleansing vessel is directly below a drying vessel provided in its lower part with means for withdrawing solvent vapour generated by the drying, and which has a floor caused to open by the action of introducing the articles to be treated into the lower vessel, and to close again automatically when the articles are raised into the drying vessel. The means for withdrawing solvent vapour could be a pump in communication with a vessel containing an adsorbent, and, though primarily designed for use with cold solvent, the apparatus was stated to be capable of use with a heated liquid solvent.

According to the present invention, an apparatus for degreasing metal and like non-absorbent articles with a volatile solvent and subsequently drying them comprises a lower section adapted to act as a solvent degreasing compartment and an upper section adapted to act as a drying compartment, means for introducing articles into either section, means for isolating the upper section from the atmosphere and from the remainder of the apparatus when the articles are in the upper section, and means for establishing, when the articles are in the drying compartment, a closed air circulation system, whereby air can be passed through the drying compartment and thence through a solvent recovery unit. In a preferred form of our invention the closed air circulation system comprises a heater, a con-

2

denser, and a fan whereby air may be passed in succession through the heater, the drying compartment and the condenser, and so back to the heater.

In such an apparatus using a forced, hot air circulation system, rapid drying of the articles can be achieved irrespective of their heat capacity, and this without entailing losses of solvent to the atmosphere, and while keeping the degreasing apparatus proper ready for immediate use when the dried articles are removed. The apparatus is particularly suitable for use in degreasing with a solvent whose vapour is heavier than air, e. g. trichloroethylene.

In one form of my invention the apparatus comprises an open-topped or tank-shaped vessel having around the walls at an intermediate height means for condensing solvent vapour, the vessel being thus divided into an upper and lower part each adapted to contain the articles to be treated, means for heating solvent in the lower part, a closed air circulation system whereby hot air can be circulated through the upper part, a lid for isolating the vessel from the atmosphere, and means to isolate the upper part of the vessel from the lower part. Preferably the last said means comprises a platform adapted to carry the articles, which platform is capable of being raised or lowered so that when in the lowered position the articles are in the lower part of the vessel and when in the raised position they are in the upper part, the platform then forming a closure between the two parts of the vessel.

In use a charge of solvent is put into the lower part of the vessel so that articles therein are immersed in the solvent, the condensing means, e. g. condensing coils to which cold water can be supplied, are put into operation, and the solvent is heated to boiling point. The condensing coils cause vapour rising from the solvent to condense and fall back into the body of solvent so that the solvent vapour is confined to the lower part of the vessel forming the degreasing zone. Articles are then loaded on to the platform, and the platform is then lowered into the solvent and left there until degreasing is completed. Preferably during this operation the lid of the vessel is closed to prevent escape from the apparatus of any solvent laden air which may rise in spite of the condensing coils, and this possibility is also minimized by having the upper part of the vessel forming, as it were, an antechamber between the degreasing zone and the atmosphere. After the articles have been degreased, the platform is raised so that when the articles are transferred

to the upper part of the vessel the platform seals off the upper part from the lower. If desired they may be left at an intermediate height for a short time to allow the majority of solvent to drain off before the platform is raised high enough to seal off the lower compartment. The lid still being closed, the fan is put into operation so as to circulate hot air through the upper part of the apparatus containing the articles, thus drying them by causing solvent still adhering to evaporate and to be carried away in the hot air stream; the vapours are removed from the air stream in the solvent recovery unit, and the air is reheated and returned to the drying compartment. When all the solvent has thus been removed the fan is stopped, the lid opened, and the articles removed. In such an apparatus, instead of using the platform for the goods as the means for separating the two compartments the goods may be supported in a basket or the like, and a flexible slutter or swinging doors may be used to cut off the drying compartment from the degreasing compartment.

In a further form of my invention particularly suitable for continuous operation, the apparatus comprises a vessel having a closable opening and having around the walls at an intermediate height means for condensing solvent vapour, that part below the condensing means constituting a zone adapted for carrying out the degreasing process, and that part above the condensing means including both an antechamber for loading and unloading the articles and a drying compartment, an endless conveyor for carrying the articles in turn through the antechamber, the degreasing zone and the drying compartment, means for isolating the drying compartment from the degreasing zone and from the antechamber when the articles are in the drying compartment, and a closed air circulation system whereby hot air can be passed through the drying compartment and thence through a solvent recovery system.

Thus the apparatus may comprise a closed vessel having condensing coils around the walls at an intermediate height and heating means in the lower part of the vessel for heating solvent placed therein so as to set up a solvent or a solvent vapour degreasing zone. A centrally disposed vertical partition is arranged in the upper part of the vessel extending on the one hand to somewhat below the level of the condensing coils and on the other hand almost to the top of the vessel, leaving only room for the passage of articles from one side of it to the other. The upper section of the vessel is thus divided into two parts, each capable of containing the articles, and each of which is in communication with the solvent degreasing zone beneath. One section is fitted with a closable opening for charging and discharging articles, and thus constitutes the antechamber, while the other section is in communication with the hot air circulation system and constitutes the drying compartment. An endless conveyor is arranged to carry articles from the antechamber down into the degreasing zone, under the partition, and up into the drying compartment; thence the articles pass over the top of the partition and back to the antechamber. Moveable doors are provided for shutting off the drying compartment from the degreasing zone and also from the antechamber and thus from the atmosphere. Suitably these doors are automatically actuated by the driving means provided for the conveyor. Preferably it is arranged that

the motion of the conveyor is intermittent, the conveyor being at rest for a short time while the articles are in the various sections of the apparatus. In using this apparatus articles are loaded on to the conveyor and are then moved down into the degreasing zone where they are freed from adherent grease and the like in the customary manner. The articles then rise from the degreasing zone on the opposite side of the partition and pass into the drying compartment. The doors to the drying compartment automatically open for this to happen and when the articles are inside they shut again, completely isolating the compartment from the atmosphere and from the rest of the apparatus. The closed hot air circulation system is then put into operation, and the articles are thus freed from adherent solvent carried up from the degreasing zone. The circulation of air is then stopped, and the conveyor then carries the articles over the top of the partition as the doors automatically open for this to be possible, and so into the antechamber. There they are unloaded and more are loaded in their place. The conveyor may be arranged to carry, e. g. three loads of articles so that one load is in the degreasing compartment while another is in the drying compartment, and the third in the antechamber for unloading and replacement.

This continuous apparatus is capable of various modifications. Thus the degreasing zone may include two or more degreasing compartments, for example, several liquor compartments together with a hot spray or vapour treating compartments. Again instead of dividing the upper part of the vessel into two by a permanent partition located within the antechamber or between the antechamber and the degreasing zone, the drying compartment may be formed of a pair of box-like members rotatable about perforated hollow axes to approach one another and thus enclose the articles on the conveyor as they emerge from the degreasing zone. The hot air is supplied to and removed from the compartment formed by the closed members through the hollow perforated axes. When drying is complete the air circulation is cut off and the box-like members are moved apart to allow the articles to progress to the position for loading and unloading.

The hot air circulation system suitable for use in any of the above forms of the invention may comprise a water-cooled condenser, a condensate trap, a blower and a heater, conduits being provided so that solvent-laden air from the drying compartment passes through the water-cooled condenser to condense out solvent vapour, and the condensate is separated in the trap and returned to the degreasing compartment through a liquid seal formed, e. g., by a U bend in the return pipe. The air conduit from the condensate trap is joined to the suction side of the blower and the delivery side of the latter is connected to the air heater, while the exit side of the air heater is connected to the inlets to the drying compartment. Suitably the air is delivered to and removed from a number of separate points of the drying compartment so that all parts of it may be swept by the air stream. In order to free the articles of the least odour which might arise from traces of solvent vapour remaining after passage through the condenser, it is frequently desirable to complete the drying with fresh air, and for this purpose the air circulation system may be provided with an inlet for atmospheric

air, a discharge to atmosphere, and a system of valves interconnected so that in one position the air circulates repeatedly through the system and that in the other air is drawn in by the pump and is discharged again after passing in turn through the heater, the drying compartment, the condenser and condensate trap. If desired the discharge to atmosphere may be through a charcoal adsorption system, or outside of the building housing the plant.

The invention will now be described with reference to the accompanying diagrams in which

Fig. I represents an elevation of one form of apparatus according to my invention.

Fig. II represents a sectional elevation of the same apparatus taken on a line 2—2 of Fig. I.

Fig. III represents a further form of my invention adapted for continuous operation.

In Fig. I and Fig. II only, like numerals represent like parts, and for simplicity the condenser and like external parts of the air circulation system have been omitted from Fig. II and Fig. III.

Referring now to Figs. I and II, the apparatus comprises a deep open-topped vessel 1 of sheet metal having at the bottom a sump 3 for solvent which can be heated by gas burners 2. A flue 14 for hot waste gases is provided extending vertically at the side of vessel 1, and the sump 3 has a removable door 30 fitted with a drain cock for emptying and cleaning purposes. At an intermediate height around the inside perimeter of the vessel 1 are condensing coils 4, through which cold water can be circulated by means not shown, and which thus set an upper limit to the solvent degreasing zone 5 constituting the lower part of vessel 1. The upper part 6 of vessel 1 constituting the drying compartment, has a lid 7 which can be slid to one side on to supports 8 when articles have to be introduced and removed; both lid 7 and the parts of walls of vessel 1 bounding the compartment 6 are lagged with insulating material 32 to minimize loss of heat during the drying operations; an insulating course 33 is also built into the walls of vessel 1 at the level of the bottom of compartment 6. A "cold-line" channel 34 to which cold water can be supplied is disposed somewhat below insulating course 33, so that the temperature gradient in the parts of the walls immediately above coils 4 can be minimized and thus transference of solvent vapour by hot air convection currents from the lower part of the vessel cut down. A horizontal platform 9 is provided inside the vessel to carry the articles being treated. This platform can be moved vertically upwards and downwards along four guides 10 (two of which are shown) by lifting gear 11 which can be operated from outside vessel 1 when lid 7 is closed. In Fig. I the platform is shown in the raised position. At the bottom of its travel the platform and any articles on it will be subject to the action of the solvent in the lower part 5 heated in sump 3. At the top of its travel the platform 9 co-acts with a ledge 12 inside the vessel at the level of insulating course 33 to form a seal between the part 6 of the vessel above the insulating course and the part 5 below coils 4. When the platform is in this raised position and lid 7 is in position, the drying compartment 6 is closed both from the atmosphere and from the degreasing vessel, and the articles on the platform are within it.

Adjacent to vessel 1 is an air heater 13 consisting of a jacket around a part of flue pipe 14, a water-cooled condenser 15 fitted with an inlet 25 and an outlet 26 for cooling water, a con-

densate trap 27 built on to the condenser 15, and a blower 16 operated by motor 29. Condenser 15 and blower 16 are mounted on staging 31. Condensate from trap 27 can be returned to sump 3 through pipe 28, and the air outlet from trap 27 is joined to the suction side of blower 16 through valve 18. A sight glass (not shown) is provided to enable the passage of condensate through pipe 28 to be observed. An inlet 20 for atmospheric air controlled by valve 22 is provided between valve 18 and blower 16, and between valve 18 and trap 27 is a discharge 19 to atmosphere controlled by valve 21. Valves 18, 21 and 22 are interconnected by linkwork 23 operated by lever 24 so that when valve 18 is open valves 21 and 22 are closed and vice-versa. By means of ducting indicated generally at 17 air can be caused to circulate by blower 16 in turn through air heater 13, drying compartment 6, condenser 15 and trap 27 and thence either out through valve 21 and outlet 19 or back to blower 16 according to the position of the valves 18, 21, and 22. The ducting 17 has a number of inlets 35 into compartment 6 to facilitate the distribution of hot air. Several outlets are similarly provided.

In using this apparatus part 5 is filled with solvent e. g. trichloroethylene, almost up to the level of coils 4, cooling water is supplied to coils 4 and to channel 34, and the burners 2 are lit so as to heat solvent in the lower part 5 of vessel 1 to boiling, vapour formed being condensed on coils 4. Articles to be degreased are put on to the platform which is then lowered into the solvent, preferably after lid 7 has been moved into position over the top of vessel 1. During this time the air circulation system is out of operation. When degreasing is judged complete cooling water is supplied to inlet 25 of condenser 15 and the platform 9 is brought to the raised position shown in Fig. II sealing off the upper part 6 of vessel 1 from the lower part 5. Lever 24 is brought to the position in which valve 18 is open and valves 21 and 22 are closed, and blower 16 is then put into operation, lid 7 being closed. Air is thus circulated through heater 13, and after being heated passes into the drying compartment 6 causing solvent adhering to the articles on platform 9 to evaporate and the vapour to be carried away in the air stream. Such vapours will be condensed out in condenser 15 and the condensate trapped in trap 27 and returned via pipe 28 to sump 3, while the air, freed from substantially all of the vapour, will return to blower 16 through valve 18 to be re-circulated. When no more condensate is seen to flow past the sight glass and the articles are thus deemed dry, lever 24 is moved so that valve 18 is closed and valves 21 and 22 open. Air is thus sucked in through inlet 20 by the blower and circulated through the system and out through outlet 19.

A short time with this position of the valves suffices to remove any odour of solvent which might otherwise remain, and blower 16 can then be stopped, lid 8 opened, the articles removed, and more articles requiring treatment introduced. The apparatus is immediately ready for treating such articles, since no re-heating of the solvent or other preparation of the degreasing zone is needed.

70 A further form of my invention will now be described with reference to Fig. III.

In this diagram the degreasing apparatus is closed except for an opening 2' in the upper part of one side. Somewhat below the bottom of opening 2' are condensing coils 3' around the inside

walls, which coils can be supplied with cooling water by means not shown. Below coils 3' the apparatus is divided by a partition 9 into two degreasing compartments 5' and 6', and solvent in these compartments can be heated by steam coils 7' and 8' respectively. A trough 10' is arranged to collect condensate from coils 3' and deliver it to compartment 5'; normally compartments 5' will be full of solvent while compartment 6' will contain only sufficient to keep coils 7' covered when in operation, and the supply of steam to that coil will be sufficient to keep the apparatus full of vapor up to coils 3'; condensate from trough 10' falling into compartment 5' will thus cause solvent to overflow partition 9' into compartment 6' to maintain the supply of solvent for vapourisation. A conveyor 11' formed of two chains (one of which is shown) spaced apart at intervals along their path by spacer bars 12' (of which three are shown) is disposed inside the apparatus 1', passing over pulleys 13' provided with suitable driving means (not shown) so that a basket of articles can be attached to a spacer bar when adjacent to opening 2' and subsequently carried down through compartment 5', over partition 9' into compartment 6', up out of the degreasing zone on the side remote from opening 2' into the upper section 4' of vessel 1', and after travelling across the top of this section 4' of the apparatus the basket comes again adjacent to opening 2' ready for unloading. Across the major portion of the apparatus extends a partition 20', space being left to permit the movement of the largest of pulleys 13'. Opening 2' is provided with a door 19' so hinged at the lower edge of opening 2' that when open part of the door projects inwards and meets the edge of partition 20'; when closed the inside portion lies adjacent to the wall of the apparatus out of the path of the baskets of articles.

On the side of partition 20' remote from opening 2' are two box-like members 14', 14' rotatable about hollow axles 16', 16', of which the portions inside the member are perforated.

One of the axles 16' is connected by conduit 17' to the air heater of the closed hot air circulation system and the other is connected by conduit 18' to the solvent recovery unit (condenser) thereof. This system is not shown in the drawing, but is equivalent to that of Figure I in all relevant respects, except that a steam operated air heater is provided and the condensate from the condensate trap is delivered to degreasing compartment 5'. The two members 14', 14' can be rotated each about one of the axles 16', 16', so that in one position the bottom faces 15', 15' thereof project vertically upwards leaving room for the passage of articles on the conveyor upwards from the lower degreasing section to the top of the section 4' of the apparatus above the members 14', 14'. In the position shown, however, the two members co-act to enclose a basket of articles shortly after it has left the degreasing section of the apparatus, thus forming a drying compartment 21', in which the basket of articles is isolated from the atmosphere and from the remainder of the apparatus. The members are provided with the necessary recesses to accommodate the suspension members of the basket, and if desired the members 14' may be edged with some resilient material substantially inert to the solvent so that a substantially air-tight compartment is formed. One basket is shown in position in the drying compartment 21'. In the position shown, the sloping lower faces 15', 15', 75

of the members 14', 14', also form a surface substantially continuous with partition 20' and the inside portion of door 19' when it is open, thus cutting off the lower degreasing compartments 5' of the apparatus from the upper part 4' of the apparatus which thus constitutes an antechamber to the decreasing compartments in which loading and unloading can proceed. Normally members 14', 14' are in the position shown in the diagram and are only moved aside when it is desired to introduce or remove a basket of articles. The members 14', 14' have been shown projecting upwards into antechamber 4', but they could equally well have been projecting downwards, so as to occupy a position between partition 20' and coils 3'. The shape of partition 20' could be modified as necessary to accommodate the members in such a position.

The driving mechanism of the conveyor (not shown) is such that the conveyors progress with an intermittent motion, a period at rest occurring when each spacer bar is in a position appropriate for loading and unloading a basket of articles. The length of the conveyor is such 25 also that when any one spacer bar is in position for loading and unloading, a basket of articles hanging from another bar is in one of the solvent degreasing compartments and another hanging from a third bar is in the drying compartment.

In using this apparatus compartment 5' is filled with a solvent, e. g. trichloroethylene, and sufficient is also put into compartment 6' to cover coils 8'. Condensing water is then supplied to coils 3' and steam to coils 7' and 8' so that the solvent circulation is set up; the apparatus is then ready for carrying out the degreasing process. The door 19' being open and the conveyor 11' being at rest in an appropriate position, a basket of articles to be degreased is hung on appropriate spacer bar 12'. The door 19' is then closed leaving a clear passage for the basket, and the conveyor is put into operation so that the basket is carried down into degreasing compartment 5'. The conveyor 11' will then automatically stop, and door 19' can be opened for another basket to be inserted and so on. When a basket rises from the degreasing compartment 6' and approaches compartment 21' members 14', 14' are separated to permit it to enter and 50 are then brought together again to enclose it, the conveyor 11' automatically stopping when the basket is in the appropriate position in the compartment. While a basket of articles adjacent to opening 2' is being unloaded and another loaded in its place the hot air circulation system is put into operation to dry articles in that basket within compartment 21' in the manner described in connection with the apparatus illustrated by Figures I and II. When this operation 55 and the loading operation are complete the air stream is cut off, door 19' is closed, members 14', 14' separated, and the conveyor caused to move on by an appropriate amount. This cycle of operations will then be continued in this manner 60 as desired, the articles being carried from the antechamber 4' in turn through solvent compartment 5', where they receive a hot liquor treatment, and through compartment 6', where they receive a solvent vapour treatment, to drying compartment 21' and thence back to the antechamber 4'.

I claim:

1. An apparatus for degreasing metal and like non-absorbent articles with a volatile solvent and subsequently drying them, comprising in combi-

hation an open-topped vessel having around its walls at an intermediate height and within a lower degreasing compartment means for condensing solvent vapour, a solvent recovery system an upper drying and a lower degreasing compartment in said apparatus each being adapted to contain the articles to be treated, means for heating solvent in the lower compartment, means for sealing off and completely isolating the upper drying compartment from said lower compartment and the atmosphere when articles under treatment are in said drying compartment, comprising an upwardly projecting ledge member disposed on the internal walls of said vessel, and a movable partition member provided with means for coacting with said ledge member, means for introducing the articles into either compartment, and a closed hot air circulating system associated with said drying compartment, whereby air can be passed in turn through the drying compartment and through said solvent recovery system.

2. An apparatus for degreasing metal and like non-absorbent articles with a volatile solvent and subsequently drying them, comprising in combination an open-topped vessel having around its walls at an intermediate height and within a lower degreasing compartment means for condensing solvent vapour, a solvent recovery system, an upper drying and a lower degreasing compartment in said apparatus each adapted to contain the articles to be treated, means for heating solvent in the lower compartment, means for sealing off and completely isolating the upper compartment from said lower compartment and the atmosphere when articles under treatment are in said drying compartment, comprising a ledge member projecting inwardly from and secured to the internal walls of said vessel, a movable partition member provided with means adapted to coact with said ledge member, means for introducing the articles into either compartment and a closed hot air circulating system communicating with said drying compartment, comprising a heater, a water-cooled condenser, a condensate trap and a blower whereby air may be caused to circulate in turn through the heater, the drying compartment, and the water-cooled condenser.

3. An apparatus for degreasing metal and like non-absorbent articles with a volatile solvent and subsequently drying them, comprising in combination an open-topped vessel having around its walls at an intermediate height and within a lower degreasing compartment means for condensing solvent vapour, a solvent recovery system an upper drying and a lower degreasing compartment in said vessel each compartment being adapted to contain the articles to be treated, means for heating solvent in the lower compartment, a platform provided with means for sealing off and isolating the upper compartment from said lower compartment and the atmosphere when articles under treatment are in said drying compartment, said platform being adapted to carry the articles under treatment, and capable of being raised or lowered so that when in the lowered position the articles are in the lower compartment of the vessel and when it is in the raised position they are in the upper compartment, and a closed hot air circulation system in communication with said drying compartment, whereby air can be passed in turn through the drying compartment and said solvent recovery unit.

4. An apparatus for degreasing metal and like non-absorbent articles with a volatile solvent and subsequently drying them, comprising in combination an open-topped vessel having around its walls at an intermediate height and within a lower degreasing compartment means for condensing solvent vapour, a solvent recovery system, an upper drying and a lower degreasing compartment in said vessel each adapted to contain the articles to be treated, means for heating solvent in the lower compartment, means for sealing off and isolating the upper compartment from said lower compartment and the atmosphere when articles under treatment are in said drying compartment, comprising a movable platform adapted to carry the articles and to be raised or lowered so that when in the lowered position the articles are in the lower compartment of the vessel and when it is in the raised position they are in the upper compartment, a ledge member inwardly projecting from and secured to the internal walls of said vessel, means carried by said platform adapted to coact with said ledge, whereby said compartments are sealed off from each other when said platform is in its completely raised position, and a closed hot air circulation system in communication with said drying compartment comprising a heater, a water-cooled condenser, a condensate trap and a blower whereby air may be caused to circulate in turn through the heater, the drying compartment, and the water-cooled condenser.

5. An apparatus for degreasing metal and like non-absorbent articles with a volatile solvent and subsequently drying them, comprising, in combination, a lower section adapted to act as a solvent degreasing compartment, an upper section adapted to act as a drying compartment, means for introducing articles into said compartments for treatment therein, means for sealing off and completely isolating said upper section from the atmosphere and from said lower section after introducing articles under treatment into said drying compartment, a solvent recovery system, and means in communication with said drying compartment for establishing a closed hot air circulation system, comprising a heater, a condenser, and a blower, and further means for selectively controlling the circulation of air through the system and in turn through said heater, said drying compartment, and said condenser.

6. An apparatus for degreasing metal and like non-absorbent articles with a volatile solvent and subsequently drying them, comprising, in combination, a lower section adapted to act as a solvent degreasing compartment and an upper section adapted to act as a drying compartment, means for introducing articles into said compartments for treatment, means for sealing off and completely isolating said upper section from the atmosphere and from said lower section after the introduction of articles under treatment into said drying compartment, a solvent recovery system, and means in communication with said drying compartment for establishing when articles under treatment are present therein, a closed hot air circulation system, comprising a heater, a water-cooled condenser, a condensate trap and a blower, together with valve control means for selectively controlling the circulation of air in turn through said heater, said drying compartment and said water-cooled condenser.

7. An apparatus according to claim 6 in which the said hot air circulation system includes an

inlet for air, a discharge to atmosphere, and a system of valves interconnected so that in one position the air circulates repeatedly through the system and in another position air is drawn in through the said inlet and discharged again through the said outlet after passing in turn through the heater, the drying compartment and the condenser.

8. An apparatus according to claim 2 in which the said hot air circulation system includes an inlet for air, a discharge to atmosphere, and a system of valves interconnected so that in one position the air circulates repeatedly through the system and in another position air is drawn in through the said inlet and discharged again through the said outlet after passing in turn through the heater, the drying compartment and the condenser.

9. An apparatus according to claim 4 in which the said hot air circulation system includes an inlet for air, a discharge to atmosphere, and a system of valves interconnected so that in one position the air circulates repeatedly through the system and in another position air is drawn in through the said inlet and discharged again through the said outlet after passing in turn through the heater, the drying compartment and the condenser.
